UNITED STATES PATENT OFFICE.

WILLIAM MARTIN, OF DETROIT, MICHIGAN.

FUELIZING MANIFOLD FOR INTERNAL-COMBUSTION ENGINES.

1,427,540.

Specification of Letters Patent. Patented Aug. 29, 1922.

Application filed April 4, 1921. Serial No. 458,484.

To all whom it may concern:

Be it known that I, WILLIAM MARTIN, a citizen of the United States of America, residing at Detroit, in the county of Wayne 5 and State of Michigan, have invented certain new and useful Improvements in Fuelizing Manifolds for Internal-Combustion Engines, of which the following is a specification, reference being had therein to the accompanying drawings.

The invention relates to manifolds for internal combustion engines and consists in the novel construction of a combination intake and exhaust manifold constituting a 15 fuelizer for forming a combustible mixture from relatively low grade fuels. The invention further consists in various features of construction as hereinafter set forth.

In the drawings:

20 Figure 1 is a side elevation of the manifold;

Figure 2 is an end elevation thereof;

Figure 3 is a cross-section on line 3—3 of Figure 1;

25 Figure 4 is a vertical section on line 4—4 of Figure 3.

My improvement is designed for use as a replacement for the intake and exhaust manifolds of internal combustion engines 30 and to this end it is designed to conform generally to the lines of the manifolds replaced. As specifically shown, A is an integral casting having an exhaust manifold portion B and an intake manifold portion 35 C, said portions being provided with the apertured bosses D, D', etc., for connection with the intake and exhaust ports in the engine block. The portion B is formed with an opening in its front extending longitudinally thereof and surrounded by a flange or bearing forming a seat for a cover plate E.

This cover plate is provided with the integral inward hollow projection F, which at its opposite ends is provided with inwardly extending annular flanges F' forming a seat or bearing for an inner tube G, thereby forming an annular space H between said inner tube and outer wall. The ends of the tubes are welded or otherwise integrated, resulting in an open ended tube located within the exhaust conduit in the path of the exhaust gases, the walls of said tube being chambered to form in effect a retort. The cover plate E is further provided with integral hollow members I and J communicating with the annular space H at opposite

ends thereof. The member I forms an elbow fitting for connection with the downwardly extending conduit K and the member J has formed integral therewith the hollow cylindrical casings L and M having their axes perpendicular to each other. The portion M is formed with an elbow turn which fits against an apertured boss N in the intake portion C, while a stud O engaging said elbow and extending inward passes through the member C and forms a clamping means for securing the portion M thereto. The plate E is also secured to the member A by tap screws P or other securing device, and there screws together with the stud O firmly secure the two castings to each other.

The fuel which is used in forming the explosive mixture is controlled by a float chamber Q, which is preferably mounted upon a 75 down-turned arm R on the member C. This arm may, if desired, be hollow, but there is no connection between the space within the the arm and the float chamber, the only function being that of a mechanical support. 80 S is a casing formed integral with the float chamber Q and connected therewith by the discharge passage S'. This casing has its upper end connected by the packing gland S² with the conduit K and into this conduit 85 projects the upwardly extending discharge nozzle T, the lower end of which is in communication with the liquid fuel entering through the passage S'. S³ is a drain plug for closing the lower end of the casing S and 90 permitting of removing sediment or water which may collect in the casing from the fuel supply. U is a port in the upper part of the casing S communicating with the conduit K and providing for the admission of air 95 thereto to be commingled with the liquid fuel.

The casing M forms a mixing chamber for vaporized fuel received from the retort and a proportionate quantity of air, the mixture being discharged directly into the intake manifold C. The mixture is controlled by a sleeve valve V within the end of the cylindrical casing M, which is ported to register with an annular series of ports V' in 105 said casing. The valve is further provided with an elongated port W connected to a tube W' extending inward within the sleeve and turned to discharge axially of the casing M. The port W is maintained in registration with the port connecting the casings L and M, the former being a valve casing 110

for a plug valve X. This plug valve is a three-way valve which is ported so that in one position it establishes communication between the casing M and the conduit J, while in another position it cuts off such communication and connects the casing M with an auxiliary fuel supply Y suitable for use in starting.

With the construction as described, in operation, the suction formed in the intake C is communicated to the casing M and from the latter either to the retort or to the auxiliary fuel supply according to the position of adjustment of the valve X. In starting, this valve X is so turned that a supply of the auxiliary fuel, such as gasoline, is directed into the chamber M, where it is commingled with air entering through the ports V'. This will form an explosive mixture which will start the engine and as soon as the manifold is sufficient warmed, the valve X is adjusted to its other position, where the auxiliary fuel supply is cut off and communication is established between the chamber M and the conduit J. This adjustment of the valve may be accomplished by a suitable connection such as the lever X' and rod X² leading to a point under the control of the operator.

30 When the valve X is adjusted in the position last-mentioned, the suction of the engine is communicated to the retort formed by the hollow member F and through the latter to the conduit K and casing S. This will cause the discharge of the low grade fuel from the nozzle T into the conduit K and at the same time air drawn in through the port U will commingle with the discharged liquid and form a vehicle for carrying it into the retort. During passage through the retort the fuel is vaporized so that a rich mixture of fuel vapor and a small amount of air is discharged into the casing M. Here a further supply of air is admitted through the ports V', resulting in the proper mixture for combustion.

The construction is comparatively simple as it is formed in the main of three castings; first, the member A with the integral exhaust manifold and intake portions B and C and supporting arm R; second, the cover member E with the integral retort and inlet and outlet connections, the latter including the valve casing L and the mixing chamber N; and third, the float chamber Q with the integral casing S containing the discharge nozzle T. In addition to these parts, there are only the valves, pipe connections and control levers and the whole construction forms a unit assembly which can be readily attached to the engine block as a replacement for the standard inlet and exhaust manifolds.

What I claim as my invention is:

65 1. A manifold comprising an exhaust por-

tion having an opening in the side thereof and an intake portion integral with said exhaust portion, a cover for said opening provided with an integral inwardly projecting retort portion, the latter being in the form 70 of an open ended tube having hollow walls, and integral inlet and outlet connections to said retort, the former being connected to a source of liquid fuel and the latter being connected to the intake manifold. 75

2. A manifold comprising an exhaust portion having an opening in its side and an intake portion integral with said exhaust portion, a cover for said opening in the exhaust portion provided with an integral inwardly projecting retort portion, the latter being in the form of an open ended tube having hollow walls, integral inlet and outlet connections communicating with the space within the retort, the former being 80 connected with a source of liquid fuel, a mixing chamber and a valve casing integral with said outlet connection, said mixing chamber communicating with said intake portion, and valves in said valve casing and 85 mixing chamber for controlling the mixture of fuel vapor and air. 90

3. A manifold comprising an exhaust portion having an opening in the side thereof, an intake portion integral with said exhaust 95 portion, and an arm depending from said intake portion, a liquid fuel float chamber supported on said arm, a cover for said opening in the exhaust manifold provided with an integral inward projection forming 100 a retort, said retort being in the form of an open ended tube with hollow walls, integral inlet and outlet connections to said retort, a conduit connecting the inlet connection to the discharge from said float chamber, a 105 mixing chamber integral with said outlet connection registering with an aperture in said intake and communicating therewith, and valves for controlling the proportion of vapor and air entering said intake. 110

4. A manifold comprising an integral hollow casting having an exhaust portion, an intake portion and a depending supporting arm, said exhaust portion being provided with an opening in the side thereof, a casting forming a float chamber and a fuel discharge chamber integral therewith, said casting being mounted upon said depending arm, a casting forming a cover for said opening and provided with an integral inwardly projecting hollow lug with openings at its opposite ends, a tube of smaller diameter within said hollow lug and integrated therewith at its opposite ends to form a hollow annular retort, inlet and outlet connections for said retort integral with said cover plate, said intake forming a connection for a downwardly extending conduit and said outlet being formed with a mixing chamber, and a valve casing integral therewith; a 120 125 130

three-way valve in said valve casing for alternatively establishing communication between said retort and mixing chamber and between said mixing chamber, and an auxiliary source of fuel, means for clamping said mixing chamber to said intake, said parts having registering ports for establishing communication therebetween, and a conduit for connecting said intake and fuel discharge chamber, the latter being ported for the admission of air, whereby the discharged fuel is carried in suspension into said retort.

5. The combination of a manifold having an exhaust portion formed of an opening in the side thereof, an intake portion integral with said exhaust portion and a depending arm, a float chamber mounted on said depending arm and having integral therewith a fuel discharge chamber, a discharge nozzle within said chamber and an air inlet port

adjacent to said discharge nozzle, a member forming a cover for said opening having an integral inward projection constituting a retort with inlet and outlet connections also integral with said cover, said outlet connection being formed with a valve casing and a mixing chamber, the latter having a port registering with a port in the intake manifold, clamping means for attaching said cover and securing said mixing chamber to said intake manifold, a valve in said valve casing for controlling the supply of vapor from the retort into said mixing chamber, and a connection between said inlet to the retort and to said discharge chamber of said float chamber through which liquid fuel and a suspensory air current are conducted to the retort.
